CLAIM

The ornamental design for a sea babies doll, as shown and described.

DESCRIPTION

FIG. 1 is a front left perspective view for a sea babies doll showing my new design;
FIG. 2 is a front elevational view thereof;
FIG. 3 is a rear-left perspective view thereof;
FIG. 4 is a rear elevational view thereof;
FIG. 5 is a top plan view thereof; and,
FIG. 6 is a bottom plan view thereof.

The broken lines indicate unclaimed portions of the design and forms no part of the claimed design.
